UNITED STATES PATENT OFFICE.

RALPH B. VESSEY, OF FLINT, MICHIGAN, ASSIGNOR TO CHAMPION IGNITION COMPANY, OF FLINT, MICHIGAN, A CORPORATION OF MICHIGAN.

SPARK-PLUG.

1,355,628.

Specification of Letters Patent. Patented Oct. 12, 1920.

Application filed September 25, 1918. Serial No. 255,583.

To all whom it may concern:

Be it known that I, RALPH B. VESSEY, a citizen of the United States, and resident of Flint, Genesee county, State of Michigan, have invented certain new and useful Improvements in Spark-Plugs, of which the following is a specification.

The invention relates to improvements in spark plugs and method of forming the same, and more particularly to the construction and method of forming the plug whereby the electrode supported by the insulator is properly sealed thereto and the insulator itself properly sealed in the shell of the plug in an expeditious manner and with a full measure of safety against fracture or breakage of the insulator or any loose joint in the sealing of the same about both the electrode and shell.

These and other objects will appear from the following description taken in connection with the accompanying drawings, which form a part of this specification and in which:

In the drawing, Figure 1 is a vertical sectional view of the spark plug parts before sealing, showing the same supported on a suitable base. Fig. 2 is a vertical sectional view showing the application of the tool for sealing the electrode and seating the insulator within the shell, and Fig. 3 is a vertical sectional view showing the tool sealing the electrode in the insulator and pressing the insulator with said electrode firmly onto the gasket within the shell, and the tool for sealing said shell about the insulator.

Like numerals of reference indicate similar parts throughout the views.

Referring to the drawing, particularly Fig. 1, 10 is a base or table having a suitable orifice 11 therein and in which the lower end of the shell 12 is inserted, said shell being of any desired form or structure as desired and having the interior bore 13 formed with the seating flange 14 and the upwardly extending top sealing flange 15.

The shell 12, when in the position described, has placed therein an insulator member 16 having the enlarged center portion 17, below which is arranged a compressible gasket 18, said gasket seating upon the flange 14 of the shell.

The insulator 16 also has a central electrode 19 arranged therein and extending downwardly therethrough, as customary in 55 spark plug construction.

The electrode 19 adjacent the upper end thereof has a flange 20 extending laterally therefrom immediately above the insulator, and a compressible gasket 21 formed of asbestos or other suitable material is arranged between said flange 20 and the top of the insulator 16.

A suitable gasket 22 is placed about the insulator immediately above the enlarged 65 center portion 17 in readiness to form a seal when the upwardly extending flange 15 of the shell is turned thereover, as herein-after described.

Referring particularly to Fig. 2, the parts 70 as shown and described with reference to Fig. 1 are shown in readiness for the first sealing operation, wherein a tool 23 having the hollow center 24 and the lower forming surface 25 is pressed downwardly over the 75 electrode 19 whereby the lower forming surface 25 thereof presses about the outer edge of the flange 20 of said electrode and firmly presses said flange around the periphery downwardly against the insulator whereby 80 the compressible gasket 21 therebeneath is firmly compressed to form a proper seal between the upper end of said electrode flange and the insulator.

Coincidentally with the sealing of the 85 flange 20 against the insulator, the tool 23, pressing as it does on the top of the insulator, will seat said insulator very firmly within the shell, and in so doing compress the gasket 18 onto the flange 14 to form a 90 gas-tight joint therebetween.

Referring particularly to Fig. 3, the parts as shown and described with reference to Fig. 2 are now ready for the next operation of sealing, which comprises the use of a 95 cylindrical tool 26, having a center bore 27 whereby it may be brought downwardly over the tool 23, the lower end of said tool being suitably formed as at 28 to turn the upwardly extending flange 15 of the shell 100 inwardly over the enlarged center portion 17 of the insulator, or against any gasket which may be about the insulator at that part, as hereinbefore referred to. As a result of

this sealing operation the inturned flange 15 of the shell, as shown in Fig. 3, will effectually retain the center insulator in its proper position within the shell, wherein it is firmly 5 pressed against the lower sealing gasket 18.

It will of course be obvious to those skilled in the art that many forms of gaskets or sealing material may be used at the joints desired to be sealed, or if the surfaces 10 are properly prepared the gaskets may be eliminated entirely, or if desired, a suitable coating of material such as a varnish of litharge or bakelite in liquid form may be placed upon the surfaces where the sealing action is to occur, and the method 15 of forming the spark plug as herein described carried out, the essential features of which are the means whereby the electrode may be properly set and sealed in the insulator and coincidentally therewith the insulator 20 itself properly seated in the shell, at which time the upper flange portion of the shell, or any other suitable means such as a threaded nut or bushing, is so positioned 25 as to hold the insulator with the central electrode sealed therein in its proper sealed position within the shell.

It will be obvious to those skilled in the art that many modifications and changes 30 may be made without departing from the spirit and scope of the invention.

Having now described my invention what I claim as new and desire to secure by Letters Patent is:

35 1. The method of forming spark plugs comprising the seating of the insulator with an electrode supported therein upon a compressible gasket within a shell having a sealing flange, pressing said electrode to seal 40 the same in said insulator, and pressing a holding flange of said shell inward and into holding engagement with said insulator to thereby secure the same in place within said shell.

45 2. The method of forming spark plugs comprising the seating of the insulator with an electrode supported therein upon a com-

pressible gasket within a shell having a sealing flange, and coincidentally pressing 50 said electrode to seal the same in said insulator and pressing a holding flange of said shell inward and into holding engagement with said insulator to thereby secure the same in place within said shell.

3. The method of forming spark plugs 55 comprising the seating of the insulator with an electrode supported therein and having a flanged part above said insulator and a sealing gasket immediately therebeneath upon a compressible gasket within a shell 60 having a sealing flange, pressing upon the flange of said electrode to seal the same against said insulator, and pressing a holding flange of said shell inward and into holding engagement with said insulator to 65 thereby secure the same in place within said shell.

4. The method of forming spark plugs comprising the seating of the insulator with an electrode supported therein and having a flanged part above said insulator and a sealing gasket immediately therebeneath upon a compressible gasket within a shell 70 having a sealing flange, pressing upon the flange of said electrode about the outer edge 75 thereof to seal the same in said insulator, and coincidentally pressing a holding flange of said shell inward and into holding engagement with said insulator to thereby secure the same in place within said shell. 80

5. The method of forming spark plugs comprising the arranging of an electrode within an insulator whereby it may be sealed therein and arranging said insulator within a shell whereby it may be sealed 85 therein, exerting a sealing pressure upon said electrode and insulator, and providing said shell with a means for retaining said insulator in sealed position while the sealing pressure aforesaid is maintained upon said electrode and insulator. 90

In testimony whereof I affix my signature.

RALPH B. VESSEY.
